UNITED STATES PATENT OFFICE.

EZEKIEL J. WILSON, OF EAST GREENBUSH, NEW YORK, ASSIGNOR TO F. C. HUYCK & SONS, OF RENSSELAER, NEW YORK, A CORPORATION OF NEW YORK.

LOOM.

Application filed May 23, 1921. Serial No. 471,640.

To all whom it may concern:

Be it known that I, EZEKIEL J. WILSON, a citizen of the United States, residing at East Greenbush, in the county of Rensselaer and State of New York, have invented certain new and useful Improvements in Looms; and I do hereby declare the following to be a full, clear, and exact description of the invention, such as will enable others skilled in the art to which it appertains to make and use the same.

The invention relates to looms, and more particularly to the mechanism for controlling the operation of the picking mechanisms which throw the shuttle or shuttles back and forth across the lay.

The invention is particularly applicable to extremely broad looms in which the lay may be from thirty to forty feet and more in length, although the invention is not confined in its application to such looms. The usual type of positively operated and timed picker stick actuating mechanism which is commonly employed in looms of moderate width have been found to be unsuited to the breadth of loom which is desirable in weaving certain kinds of fabrics such, for instance, as endless felts for paper-making machines. For properly throwing the shuttles across the extremely long lays of this class of looms the picker sticks should be actuated by springs which are put under tension or "cocked" and then released or "fired" to throw the shuttles, and the present invention is designed to control and properly time picking mechanisms of this character. In the construction in which the invention has been embodied the spring cocking and firing mechanisms for each picker stick are operated for each beat of the lay. Each picker stick should, however, be operated to throw a shuttle only when there is an empty shuttle box at the opposite end of the lay to receive any shuttle which may be thrown. The picking mechanisms are controlled to secure this result by electro-magnetic devices, the circuits for which are so controlled that each picking mechanism is rendered inactive to throw a shuttle whenever there is a shuttle in the shuttle box at the other end of the lay. If there is a shuttle in the shuttle box at one end of the lay the actuating mechanism for the picker stick at that end of the lay will be active to throw a shuttle provided there

is no shuttle in the box at the other end of the lay while the mechanism for actuating the picker stick at the other end of the lay will be rendered inactive. The electro-magnetic control will thus insure the proper timing of the widely separated picker stick actuating mechanisms to throw a shuttle back and forth across the lay or to throw a number of shuttles successively first from one and then from the other end of the lay.

A switch may also be provided by which the operator may conveniently interrupt the operation of both picker sticks for any desired number of picks in order to keep the harness and shuttle in proper time in case it should become necessary to interrupt the regular sequence of operations, as upon the occurrence of a broken shuttle thread.

The preferred form of the invention is shown in the drawings in which Figs. 1 and 2 show in elevation and somewhat diagrammatically the picking mechanisms at opposite ends of the lay; Fig. 3 is a detail of the circuit controlling devices which are operated by a shuttle in the shuttle box at the end of the lay; Fig. 4 is a diagram indicating the circuits for the electro-magnetic controlling devices; and Fig. 5 is a detailed view of a part of the picker mechanism.

As shown in the drawings the lay 2 is carried upon the upper ends of the legs 4, which are secured at their lower ends to the rockshaft 6. The loom shown is provided at each end of the lay with two shuttle boxes 8 which are vertically movable to bring either box into active position at the end of the lay by any suitable mechanism (not shown). A picker stick 10 is mounted on the end leg 4 at each end of the lay and the upper end of the stick is connected by a strap 12 with a sliding block 14 arranged to enter the shuttle box which is in active position at the end of the lay and to engage the end of the shuttle. A roll 16 is fixed to the guideway for the block 14 and acts upon the strap to limit the forward movement of the block by the picker stick.

The picker stick is pivoted upon a bracket 18 secured to the leg 4 and is connected by a link 20 and chains 22 with heavy springs 24 which tend to move the picker in a direction to throw the shuttle across the lay.

The mechanism for retracting the picker stick and thus cocking or tensioning the springs 24 comprises a lever 26 mounted on

the pivot for the picker stick and provided with a lug 28 arranged to engage a lug 30 on the stick. When the picker stick is retracted or cocked it is retained in retracted 5 position by a latch 32 pivoted to the leg 4 and arranged to engage a lug 34 on the stick. The means for disengaging the latch to release or fire the picker comprises an arm 36 on the lever 26 which carries an adjustable tappet 38 adapted to engage the lower end of a bolt 40 which slides vertically in the latch 32. When the bolt 40 is in its lower position it is in position to be engaged by the tappet 38 and to cooperate 10 therewith in disengaging the latch 32 to release or fire the picker. If the bolt is raised its lower end is withdrawn from the path of the tappet 38, thus rendering the latch disengaging or firing mechanism inactive 15 until the bolt is again returned to its lower position.

The levers 26 and their connected arms 36 are oscillated for each pick or beat of the lay, the movement in one direction retracting 20 the picker stick which has been released for the previous pick and the final movement in the opposite direction releasing the picker stick corresponding to the bolt 40 which is in active position. Each lever 26 25 also carries an arm 42 which is connected by a link 44 with a slide 46 for returning the shuttle engaging block 14 to position beyond the end of the shuttle boxes when the lever is rocked to retract the picker stick previously 30 released. The levers 26 are oscillated in proper time for each beat of the lay by means of a crank 48 connected by a link 50 with the right hand lever at a point above its pivot and connected with the left hand lever through the links 50, 52, lever 40 54, and link 56 at a point below its pivot.

The position of each bolt 40 and therefore the operation of the corresponding picker stick is controlled by an electro-magnet in 45 the form of a solenoid indicated at 58 which is secured to the lay leg 4 and the core or armature 60 of which is connected by a link 62 with the upper end of the bolt. The circuit for the solenoid 58 at the left end of 50 the lay is controlled by circuit closing devices arranged at the right hand end of the lay and operated to close the circuit by a shuttle within the shuttle box which is in position at that end of the lay. The circuit 55 closing devices comprise an adjustable contact screw 64 mounted in the upper end of an arm 66, the lower end of which is secured to a rod 68 carried by a bracket 70 secured to the lay bed which is constructed of wood 60 and therefore serves to insulate the parts carried by the bracket. The contact 64 at the right end of the lay is connected by a circuit wire with one terminal of the solenoid 58 at the left hand end of the lay while the 65 contact 64 at the left hand end of the lay is

connected by a circuit wire with one end of the terminal of the solenoid 58 at the right hand end of the lay. The other terminals of the solenoids are connected with circuits which include the metal parts of the loom 70 and therefore the spring pressed metallic friction plate 72 with which each shuttle box is provided and which is forced outward by a shuttle within the box, but is normally held in its inner position in the absence of 75 a shuttle, as indicated in Fig. 3. The contact screw 64 is so arranged that it registers with the plate 72 of the shuttle box which is in position at the end of the lay and is so adjusted that it will be engaged by the plate 72 80 if the plate is held in its outer position by a shuttle, but will be out of contact with the plate if the plate is in its inner position as it will be in the absence of a shuttle. The circuit through the solenoid 58 at the right 85 hand end of the lay will, therefore, be closed whenever there is a shuttle in the active shuttle box at the left hand end of the lay and the bolt 60 at the right hand end will be raised to prevent the release of the right 90 hand picker stick. The active shuttle box at the right hand end of the lay will at this time be empty and the circuit through the left hand solenoid will be broken so that the bolt 40 at this end of the lay will be in position to render the picker stick releasing devices active so that the picker stick at this end of the lay will be released and will be actuated by its spring to throw the shuttle across the lay. The converse is true in case 95 there is a shuttle in the active shuttle box at the right hand end of the lay and an empty shuttle box in active position at the left hand end of the lay. The contact devices and solenoids will thus act to accurately control and time the release of the picker sticks to throw a shuttle back and forth across the lay or to throw a plurality of shuttles successively first from one end and then from the other end of the lay. In order that the 100 operator may conveniently interrupt the operation of both picker sticks for any desired number of picks, as may become desirable during the operation of the loom, a switch indicated at 74 in Fig. 4 is so arranged in the 105 solenoid circuits that the closing of the switch will complete the circuit through both solenoids and thus cause the solenoids to withdraw both of the bolts 40 and retain them in retracted position until the switch 110 is again opened. By closing the switch, therefore, the operator may discontinue the operation of both picker sticks for any desired number of picks and then restore the shuttle control by opening the switch. 115

While it is preferred to employ the specific construction and arrangement of parts shown and described in embodying the invention in a loom in which, by reason of the length of the lay, the picking mechanisms 120

are widely separated and therefore ill-adapted for mechanical control from the opposite end of the lay it will be understood that this construction and arrangement is 5 not essential to the broader features of the invention and may be varied or modified as found desirable or best suited to the construction and mode of operation of the loom in which it is to be embodied.

10 What is claimed is:

1. A loom having, in combination, a lay, picking mechanism at each end of the lay including a picker stick, electro-magnetic means for controlling the operation of each 15 picking mechanism by a shuttle at the opposite end of the lay.

2. A loom having, in combination, a lay, picking mechanism at each end of the lay including a picker stick, electro-magnetic 20 means for controlling the operation of each picking mechanism, and shuttle operated circuit controlling means for each picking mechanism located at the opposite end of the lay.

25 3. A loom having, in combination, a lay, picking mechanism at each end of the lay including a picker stick, electro-magnetic means for rendering each picking mechanism inactive to throw a shuttle, and shuttle operated circuit closing means for each 30 electro-magnetic means at the opposite end of the lay.

4. A loom having, in combination, a lay, a spring actuated picker stick at each end of 35 the lay, cocking and firing mechanism for each picker stick operated at each beat of the lay, and electro-magnetic means for controlling the firing of each picker stick from the shuttle box at the opposite end of the lay.

40 5. A loom having, in combination, a lay, a spring actuated picker stick at each end of the lay, cocking and firing mechanism for

each picker stick, operated at each beat of the lay, and electro-magnetic means for rendering each firing mechanism ineffective 45 whenever there is a shuttle in position to be thrown by the picker stick at the opposite end of the lay.

6. A loom having, in combination, a lay, a spring actuated picker stick at each end of 50 the lay, mechanism for retracting the picker sticks operated for each beat of the lay, means for latching each picker stick in retracted position, releasing means for each stick operated for each beat of the lay, an 55 electro-magnet for controlling the operation of each releasing means, and means for controlling the circuit of each magnet by a shuttle at the opposite end of the lay.

7. A loom having, in combination, a lay, 60 a spring actuated picker stick at each end of the lay, mechanism for retracting the picker sticks operated at each beat of the lay, means for latching each picker stick in retracted position, releasing means for each 65 stick operated at each beat of the lay, an electro-magnet for controlling the operation of each releasing means, means for controlling the circuit of each magnet by a shuttle at the opposite end of the lay, and means 70 under the control of the operator for temporarily closing the circuits of both magnets.

8. A loom having, in combination, a lay, a spring actuated picker stick at each end of 75 the lay, cocking and firing mechanism for each picker stick operated at each beat of the lay, electro-magnetic means for controlling the firing of each picker stick from the shuttle box at the opposite end of the lay, and means under the control of the operator 80 for causing the electro-magnetic means to interrupt the firing of the picker sticks.
